(57) **CLAIM**

I claim the ornamental design for a tent with elephant theme, as shown and described.

DESCRIPTION

FIG. 1 is a perspective top view of a tent with elephant theme showing the new design; and

FIG. 2 is a front view of the invention showing the new design;

FIG. 3 is a top view of the invention showing the new design;

FIG. 4 is a perspective side view of the invention showing the new design;

FIG. 5 is a left side view of the invention showing the new design;

FIG. 6 is a right side view of the invention showing the new design; and,

FIG. 7 is a bottom view of the invention showing the new design.

The broken lines shown are included for the purpose of illustrating portions of the article which form no part of the claimed design.
